LIFT TRUCK

Clifford Brooks Stevens, Milwaukee, Wis., and Russell W. Daniels, Minneapolis, Minn., assignors, by mesne assignments, to Minneapolis-Moline, Inc., Hopkins, Minn., a corporation of Delaware

Filed Aug. 22, 1962, Ser. No. 71,416

Term of patent 14 years

(Cl. D14—3)

Fig. 1.

Fig. 2.

Fig. 4.

Fig. 3.

FIG. 1 is a side elevation of a lift truck showing our new design;

FIG. 2 is a top plan view of the lift truck of FIG. 1;

FIG. 3 is a front elevation of the lift truck of FIG. 1; and

We claim:

The ornamental design for a lift truck, as shown and described.
